UNITED STATES PATENT OFFICE.

ELMER WILLIAM SMITH, OF LOS ANGELES, CALIFORNIA, ASSIGNOR OF ONE-HALF TO
ELIZABETH O. ALLEN, OF LOS ANGELES, CALIFORNIA.

MUCKER.

Application filed January 21, 1921. Serial No. 438,876.

To all whom it may concern:

Be it known that I, ELMER WILLIAM SMITH, a citizen of the United States, residing at Los Angeles, in the county of Los Angeles and State of California, have invented new and useful Improvements in Muckers, of which the following is a specification.

This invention relates to muckers and methods of handling and transporting materials, particularly such as are employed in the building arts, or such as are to be removed in excavation work, and it has for its object to provide a novel mucker as well as a novel method of the general character stated whereby the construction of roadways, buildings, tunnels and other works will be greatly facilitated.

Ordinarily in the construction of buildings, roadways, dams, tunnels and like works, the materials employed, such, for instance, as the ingredients of concrete, are deposited in a mass adjacent to a fixed mixer and fed thereinto in charges which are placed in the mixer by means of wheelbarrows and other crude devices as needed, or as in the case of roadway building or street paving the materials are first deposited all along the street or roadway portion to be paved, and then manually placed in the mixer as such mixer is advanced along the street or roadway as the paving or a layer thereof is deposited or laid.

In accordance with the present invention, a preferably motor-propelled mucker is provided, and in the construction of works of great magnitude, a plurality of such muckers are employed; the mucker herein disclosed is susceptible of manipulation by a single operator who may cause the mucker to pick up material, deposit the same in a bin or hopper embodied in the mucker, steer and drive the mucker to and from the supply of material to the place of deposit or mixing of the same, and cause the discharge of batches or measured charges of the material at such place of deposit or mixture. In constructing my improved mucker, I therefore embody in a unitary structure, motive means for the propulsion thereof (either forwardly or in the reverse direction) whereby the mucker may be urged into a centralized de-

posit or supply of material, as well as propelled to transport such material, steering means, means for picking up the material, means for operating said second named means in the attacking of the supply and whereby the picked up material may be caused to be deposited in a suitable receptacle likewise embodied in the mucker, means whereby the material may be discharged from the mucker, and means subject to the control of an operator whereby the functioning of any of the above mentioned means may be controlled.

In employing my novel method in building operations, I preferably place the materials, such as the ingredients of concrete, or any other material which may be conveyed by my method, at point which I term a "centralized" point of supply. Such centralized supply may consist of a relatively large supply of the material suitably located and sufficient for certain portions or sections only of a building, roadway or the like, or such centralized supply may consist of all the material of a given character to be employed in the work; likewise, in concrete construction, such centralized supply may comprise only dry ingredients of the concrete, mixed or separately considered, which may be taken in measured charges to several mixing stations, or to a mixing station, advancing with the work, as the case may be, by a mucker or by muckers whereby the materials are delivered into the mixer or mixers as required; or, in certain cases, I find it advantageous to mix all the ingredients of concrete at a single point, in which case the mixed concrete becomes the "centralized supply," the motor mucker or motor muckers coming to such centralized supply for a charge, or a plurality of charges, at each trip, and transporting such charge or charges to the place of deposit or reception where the mucker operator or driver causes the discharge thereof as required.

With the above and other objects in view, including the provision of a motor mucker of the general nature above outlined, which will be relatively simple and inexpensive in construction and organization taken in connection with positiveness and reliability in operation, the invention consists in the novel

and useful provision, formation, combination, association, and interrelation of parts, members, features, and steps, all as herein-after described, shown in the drawings, and 5 finally pointed out in claims.

In the drawings:

Figure 1 is a side elevation of a mucker constructed and organized to embody the invention;

10 Figure 2 is a fragmentary plan view of the same;

Figure 3 is a front elevation of the same;

15 Figure 4 is a longitudinal vertical sectional view of a roadway, a mucker embodying the invention being shown as employed to supply ingredients of concrete or the like from a centralized source of supply to a concrete mixer and distributor located at a distant point where the material is being deposited as the road making proceeds;

20 Figure 5 is a fragmentary diagrammatic plan view of a street in process of being paved and of intersecting streets, a novel method of supplying the ingredients of concrete from a centralized supply located in an intersecting street to a mixer and distributor located at the point where the mixed concrete is being deposited being illustrated; and

25 Figure 6 is a side elevation of a modified form of the invention, a motor truck having a building material receiving body being shown as equipped with means which convert the same into a mucker.

30 The parts in the several figures are designated by reference characters.

Referring with particularity to the drawings, in the form of the invention shown in Figures 1 to 5, inclusive, thereof, A 40 designates a motor tractor, B designates supporting means for a skip C and a bin or hopper D, E designates operating means for the skip C, and F designates a concrete mixer and distributor.

45 The motor tractor A is shown as of conventional form and is preferably propelled by an internal combustion motor through suitably arranged gearing by means of which the driving or traction wheels or elements may be driven in either direction, and has a suitable steering means 7, a power shaft 8 for actuating the skip of the mucker, and suitable means of power and gearing control.

50 The supporting means B is shown as comprising a framework consisting of suitably arranged frame members 9 the framework being shown as mounted upon and surrounding the tractor A and the operator's seat 10 thereof.

The skip C is shown as a scoop-like body 11 of heavy sheet metal, and with a relatively wide forward lip or cutting edge 12 which is reinforced or formed of suitable

65 steel or like wear-resisting material adapted

to be forced into building material or the like, and with a relatively narrow throat or discharge spout 13 at its rearward or discharge end. Between the ends 12 and 13 the skip bottom is preferably formed as best 70 shown in Figure 1, that is with a short bottom portion 14 at the cutting edge in angular relation to a longer bottom portion 15 disposed rearwardly thereof; the sides 16 of the skip are shown as having upper edges 75 lying, in the main, approximately in the plane of the discharge end and the cutting or leading edge of the skip, so to form a suitable receptacle for the reception and conveyance of the material. At the extreme 80 discharge end or spout portion of the skip the side walls are arranged as at 17 to provide proper depth of discharge spout and guide the material being discharged therethrough. Between side members of the 85 framework B, I provide a pair of skip-supporting arms 18 which arms are secured to the skip at their outer ends as at 18^a, rotatably journaled in the framework B at their inner ends as by means of a shaft at 19, so 90 mounting the skip in the framework for rotation about a horizontal axis.

At a point disposed forwardly of and higher than the axis of rotation of the skip, I rotatably mount, by means of a shaft 20, 95 in the framework, a pair of gear sectors 21 each of which is provided with teeth 21^a; at their forward ends the sectors are provided with a roller device 22 which abuts against the skip bottom and co-acts therewith in the 100 operation of the skip. These sectors are comprised within skip operating means E.

The hopper D is shown as comprising a suitable material receptacle secured to the rearward portion of the framework or supporting means B and as having a receiving chute 23 extending forwardly in the framework B to the point of discharge of the skip C when the same is in its uppermost or discharging position. The entire bottom 110 area of the hopper, including the chute portion thereof, is inclined rearwardly to the end, that, upon the opening of a gate 24 hinged as at 25, to the rear wall 26 of the hopper, and adapted to close a discharge 115 opening 27 at the rear of the hopper, the material may be discharged into the receiving hopper of the mixer F. Gate controlling means h are preferably provided and such means may comprise a gate latch 120 28, linkage 29, and a handle 30 located in such position that the operator may conveniently manipulate the same from his seat.

The operating means E may comprise in addition to the roller and sector device hereinbefore described, a pair of shafts 31, one of which may underlie each sector 21, means e for engaging and disengaging the shafts 31 with the power shaft 8 of the tractor for rotation of the shafts thereby in either of their 125 130

directions of rotation, and controlling means *e*' for said means *e*. Each shaft 31 is journalled in the framework A as at 32 and has secured thereto a worm 33 which meshes with the teeth 21^a of the respective sector 21. The means *e* may comprise for each shaft 31, a pair of oppositely driven clutches 32 mounted for rotation upon the respective shaft and each driven by a gear 33 from a drive gear 34 at the respective end of the power shaft 21 which may extend transversely of the tractor A from one shaft 21 to the other, and a pair of clutches 35 mounted upon each shaft 21 and slidably longitudinally thereof. Such clutches 35 are mounted for rotation with their shafts and are each faced for engagement with the corresponding clutch 32. The controlling means *e*' may be a lever 36 pivotally mounted upon the framework A, as at 37, within convenient reach of the operator, and linkages 38 extending to all the slidable clutch members 35; by arranging the lever and linkages so that three positions of the lever are employed, namely, neutral, forward and reverse, and so that the slidable clutch members 35 are correspondingly positioned with respect to driving their shafts upon engagement or disengagement with corresponding drive clutch members 32, the sectors may be rotated about their axis in either direction so as to drive them forward or in the reverse direction; the worms meshing with the sector teeth will hold the sectors in any of their positions of adjustment, and through the sectors the skip will be held in any of its positions.

The roller device 22 of the sectors 21 lying against the bottom of the skip C, the skip may be adjusted as to elevation, both for the purpose of properly picking up material, as may be required by varying conditions, and for the purpose of elevating such picked up material, either to the intermediate position of skip adjustment where the skip will act as a receptacle or bin, or to uppermost or "inverted" position of the skip where the material in the skip will be discharged into the chute of the hopper, by proper manipulation of the controlling lever 36, to move the sectors into proper position, as will be readily understood by those skilled in the art to which this invention appertains. Upon retraction of the sectors, the skip will follow the roller device in its descent, due to the attraction of gravitation.

The method of making roadways illustrated in Figure 4 presents advantages over ordinary methods in that a "centralized" supply of road-making material, such, for instance, as ingredients of concrete shown in a pile at 39 may be employed as a source of supply for the mixer and distributor F shown as located at the actual point of work; as the concrete is deposited the mixer advances, so to always keep the same in the zone of the

work. The motor mucker is shown in the position assumed in attacking the pile of material 39, the skip being properly adjusted as to elevation; upon the application of power to the driving wheels through the power controlling elements of the motor tractor the skip will be driven into the material and filled. The operator may then stop the forward movement of the mucker, and by proper manipulation of controlling lever 36 the operator may cause the skip to be elevated to dump or discharge the material therein into the bin or hopper at the rear of the mucker and then again lower the skip to attack the pile of material to refill the skip. The skip may then be moved to its intermediate position as shown in dotted lines, and act as a receptacle or bin for the charge of material therein, whereupon the mucker may, by the use of the motor tractor reverse gear, be backed along the roadway to the mixer: in case the skip is designed to hold just the right amount of material for one mixer charge, the gate of the hopper may be opened and the material discharged directly into the mixer; after such mixer charge has been deposited upon the roadway, or otherwise disposed of, the skip may be raised and its charge discharged into the chute and hopper and therethrough into the mixer. The advantages of such method over the ordinary method which consists in depositing the materials all along the roadway and conveying or shoveling the material as the mixer advances along the roadway is apparent.

In Figure 5, I have illustrated a method of paving streets, roadways and the like which possesses great advantages in certain cases. In this figure a street being paved is shown at 40, intersecting streets at 41, 42, and 43, and the "centralized" supply of material for the concrete employed in paving two blocks of the street 40 is shown at 44 where a plurality of bins adapted to hold the required dry materials are shown; the mucker or a plurality of muckers embodying the invention carry the material from the bins, where proper measured charges of the dry ingredients are successively delivered into the skips of the muckers and carried to the mixer F which is located in the zone where the concrete is being deposited as at 45. The muckers in their forward and reverse movement so keep the mixer or mixers supplied; as the work proceeds and the intersecting street 42, wherein, at one side of the street being paved, the centralized supply is located, is reached, the work in that direction may be stopped, and that portion of street 40 lying between the streets 41 and 42 paved by beginning the work of depositing the concrete at the intersection of streets 40 and 41, the muckers working shuttle-fashion in carrying the material from the centralized supply toward

street 41. When the work on the two blocks or other predetermined street lengths, one located at each side of the "centralized" supply has been completed the centralized supply has been exhausted and the next two sections of street are supplied from a second "centralized" supply from which the muckers may carry material in both directions. This method has many advantages over ordinary methods, as for instance, the advantage of permitting the use of intersecting streets during the paving process of street 40. The centralized supply bins need not entirely close the alternating streets in which they are located as usually one half of the width of such streets is all that is required for the supply bins.

In the modified form of the invention shown in Figure 6, a framework G is shown as detachably applied to the forward portion of a motor truck H of conventional form having a body 46 suitable for the carrying and discharge of building materials and the like; a skip I is mounted in the framework G and is operated through segments 47 which are driven through suitably controlled gearing by means of the engine of the motor truck, the general organization and mode of operation of parts being similar to the parts of the skip and operating means therefor described in connection with the other figures; however, in this form of the invention I preferably employ a conduit or chute 48 fixed in the framework G in position to receive the material picked up and discharged thereinto by the skip I when the same is elevated to its uppermost position; this chute is inclined downwardly and its discharge end 49 is positioned to discharge material into the body or receptacle 46 of the motor truck H. The chute 48 bridges the space occupied by the driver of the vehicle and the transferring of the material from skip to receptacle is preferably overhead as in the embodiment of the invention hereinbefore described. By lowering the skip I the driver of the motor truck H may cause the same to be advanced into the material to be carried by the truck by advancing the truck; by proper manipulation of the truck and its skip, a pile of the material may be readily cleaned up especially if the pile can be attacked from various directions. When it is desired to use the motor truck for other purposes the skip and its adjuncts including the entire framework G may be detached.

It will be understood that in picking up material from a pile, and transferring the same to the bin or receptacle at the rear of the mucker, the material is elevated to a point higher than the operator's head and in fact passes over the operator during the transferring thereof; the operator so being positioned in the preferred form of the device that he may observe all requisite details

of movement, both as to locomotion in a forward direction and as to the backing up of the mucker in delivering material from a centralized supply base to a point of use, as well as the movements and working of the skip.

I do not desire to limit myself to the specific disclosure herein, but reserve the right to vary the mechanism of the mucker and the steps of the method, in practicing the invention, and all without departing from the spirit of the invention and the terms of the following claims.

Having thus disclosed my invention, I claim and desire to secure by Letters Patent:

1. A mucker of the character described comprising a skip mounted for elevating and lowering movements, and means having slidable contact with the skip, said means being capable of movement from one extreme position to another in which said skip is caused to occupy scooping, load-retaining, and dumping positions.

2. A skip comprising a scoop-like body including a short bottom and forward portion, a longer bottom, an intermediate portion in angular relation to the short bottom portion and rearwardly thereof, a relatively wide forward lip formed on the short bottom portion, a relatively narrow throat portion at the rear of the longer bottom portion, and side portions having their upper edges lying approximately in the plane of the throat portion and the forward lip.

3. A mucker of the character described comprising a skip mounted for elevating movement, and rotatable means having rolling contact with the skip whereby when said means is rotated the skip will occupy scooping, load-retaining and dumping positions.

4. A mucker of the character described comprising a skip pivoted to swing about the horizontal axis, and rotatable means having slidable contact with the skip whereby when said means is rotated the skip will occupy scooping, load-retaining and dumping positions.

5. A mucker of the character described comprising a skip pivoted to swing about a horizontal axis, and rotatable means movable about an axis above and at one side of the axis of the skip, said means having slidable contact with the skip so that when rotated the skip during elevation will occupy scooping, load-retaining and dumping positions in the sequence mentioned.

6. A mucker of the character described comprising a skip mounted to swing about a horizontal axis, a pair of spaced gear sectors mounted to simultaneously swing about a horizontal axis disposed above and at one side of the axis of the skip, and rollers carried by the sectors and engageable with said skip for the purpose described.

7. A mucker of the character described comprising a container mounted for elevating movement, and means having rolling contact with the container whereby when 5 said means is moved the container will occupy scooping, load-retaining, and dumping positions in the sequence mentioned.

8. A mucker of the character described comprising a skip mounted for elevating 10 movement, and toothed means having sliding contact with the skip whereby when said means is actuated the skip will occupy scooping, load-retaining, and dumping positions.

9. A mucker of the character described 15 comprising a skip mounted for elevating movement, and gears of substantially semi-circular form having sliding contact with the skip and operable to cause the skip to

occupy scooping, load-retaining, and dumping positions.

10. A mucker of the character described comprising a skip pivotally mounted to swing in a vertical plane, sector gears having sliding contact with the skip, and worms engageable with the gears for actuating the latter to cause the skip to occupy 20 scooping, load-retaining, and dumping positions in the sequence mentioned.

In testimony whereof, I have signed my name to this specification in the presence of 30 two subscribing witnesses.

ELMER WILLIAM SMITH.
